UNITED STATES PATENT OFFICE.

CHESTER FRANK STANLEY, OF ASHLAND, KENTUCKY.

AIRPLANE.

1,345,970.

Specification of Letters Patent. Patented July 6, 1920.

Application filed June 2, 1919. Serial No. 301,226.

To all whom it may concern:

Be it known that I, CHESTER FRANK STANLEY, a citizen of the United States, residing at Ashland, in the county of Boyd 5 and State of Kentucky, have invented new and useful Improvements in Airplanes, of which the following is a specification.

This invention relates to airplanes and especially means rendering an airplane more safe in operation, the machine being equipped with means for arresting the downward movement of the machine in case of failure of the engine or loss of control of the machine thereby enabling the machine with its 15 occupants to make a safe landing without injury to the occupant or serious breakage of the machine.

A further object of the invention is to provide in connection with a system of 20 parachutes, means under the control of the operator of the machine for adjusting the angle of said parachute with respect to the fuselage and remainder of the machine, thereby enabling the machine to be properly 25 guided and balanced during the descent thereof.

A further object of the invention is to provide in conjunction with the fuselage, and supporting plane, a fire extinguishing 30 apparatus together with means for adjusting the apparatus along the top of the fuselage in order that the contents of the container of the fire extinguisher may be directed on any desired portion of the machine which may be in flames.

With the above and other objects in view, the invention consists in the novel construction, combination and arrangement herein fully described, illustrated and claimed.

40 In the accompanying drawings:

Figure 1 is a side elevation of an airplane showing the safety mechanism of this invention in its applied relation thereto.

Fig. 2 is a plan view of the same.

45 Fig. 3 is a vertical longitudinal section through the fuselage and the parts intimately associated therewith.

Fig. 4 is a side elevation of one of the parachutes.

50 Fig. 5 is an enlarged fragmentary vertical section through one of the supports of the parachute.

Fig. 6 is a similar view showing the folded position of the parts of the parachute.

Fig. 7 is an enlarged horizontal section 55 on the line 7—7 of Fig. 6.

Fig. 8 is a diagrammatic view of the wiring system.

Referring to the drawings. 1 designates the fuselage of an airplane, 2 the tractor 60 propeller thereof, 3 and 4 the top and bottom supporting surfaces or planes respectively forming the laterally extending wings of the machine, 5 the vertical rudder, 6 the horizontal rudder, and 7 the landing 65 base which in the present instance is shown in the form of a hydroplane float, the same being connected to the bottom of the fuselage 1 by a suitable connecting frame structure 8. The fuselage is shown as provided with two cock pits one 9 for the aviator and the other 10 for the passenger or 70 observer.

In carrying out the present invention, I employ front and rear sets of parachutes 11, 75 the arrangement of which is best illustrated in Fig. 2, one set of parachutes being arranged in front of the wings 3 and 4 and another set being arranged in rear thereof. It will also be observed that the parachutes 80 11 are arranged at opposite sides of the fuselage 1. By the reason of the arrangement of the parachutes, they act to properly balance the machine as it descends from an altitude to the ground, the parachute serving to retard the descent and enable the machine to land without serious damage.

Projecting laterally from the opposite sides of the fuselage and secured to the latter are outriggers 12 which are provided 90 with bearings for the front and rear shafts 13 extending transversely of and across the fuselage and out through the ends of the outriggers 12. Fast on the shaft 13 within the fuselage 1 are pulleys 14 and working 95 around said pulleys is a flexible rope or cable 15 which also passes under directional pulleys 16 within the fuselage as shown in Fig. 3. The cable 15 is connected to the hub or shaft 17 of an electric motor 18 100 which is energized from a battery 19 or other source of electric energy as shown in Fig. 8, the circuit being controlled by a switch 20 within reach of the operator or aviator in his seat 21 within the fuselage. 105

Each of the parachutes 11 comprises a tubular shaft or upright 22 in which is slidably arranged a shaft section 23 adapted

to be projected outwardly for spreading the parachute 11 by means of a coiled spring 24 held within the tubular shaft 22 as shown in Figs. 4, 5, and 6. The main body of the 5 parachute 11 is formed like an umbrella and comprises a plurality of radiating ribs 25 which are connected pivotally at their lower extremities to a runner 26 slidable on the member 22. Extending laterally 10 from the lower extremity of the member 23 are studs 27 which, when the parachute is folded, as shown in Fig. 6, are adapted to be engaged and held beneath the arms 28 of a latch 29 pivotally mounted at 30 in a base 15 section 31 of the shaft of the parachute as illustrated in Figs. 5 and 6. The section 31 is fast on the respective shaft 13 and adapted to swing and rock therewith. The upper end of the section 31 is extended into cup 20 form as shown at 32 so as to contain the latch 29 and is also adapted to contain one or more electric magnets 33 which attracts an armature 34 pivotally mounted at 35 within the cup portion 32 of the shaft section 31, said armature carrying a catch 36 adapted to engage over the ends of the arms 28 to hold the parts in the collapsed condition shown in Fig. 6. When the magnets 33 are energized, they affect the armature 34 30 and they release the latch 29 and allow the parachute to be spread by the action of the spring 24 and the air resistance beneath the body of the parachute 11. The magnets 33 are arranged in the same circuit with the 35 motor 18 and battery 19 as shown in Fig. 8, and thus all of the parachutes are simultaneously released when the operator moves the switch 20. The operator is also enabled to energize the motor 18 and cause 40 the same to turn in either direction for turning the shaft 13, thereby enabling the parachute to be disposed at any desired angle with relation to the fuselage to effect a safe descent of the machine.

45 Extending in a fore and aft direction above the fuselage, is a guide rail 37 connected to the fuselage by supports 38, the latter being also provided with bearings for the shaft 39 of pulleys 40 around which 50 passes a flexible rope or cable 41, attached to the arm 42 of a movable carriage 43 carrying a container 44 for fire extinguishing liquid or fluid, the latter having a flexible discharge hose 45 supported by a hook 46 55 extending from the container 44. An operating cable 47 extends around a pulley 48 on one of the shafts 39 and downward into the fuselage where it passes around the hub of another electric motor 49 the energizing circuit of which is controlled by another switch 50 within reach of the aviator as shown in Fig. 3. The operator may thus 60 shift the fire extinguishing device longitudinally of the fuselage to any desired point.

What I claim is:—

1. In a flying machine, the combination with the fuselage, and wings extending therefrom, of outriggers projecting from the fuselage at opposite sides thereof and in front and in rear of said wings, and front and rear sets of normally collapsed parachutes attached to said outriggers. 65

2. In a flying machine, the combination with the fuselage and wings extending therefrom, of outriggers projecting from the fuselage at opposite sides thereof and in front and in rear of said wings, and front and rear sets of normally collapsed parachutes attached to said outriggers, and 70 means for holding and releasing said parachutes and permitting them to spread. 75

3. In a flying machine, the combination with the fuselage and wings extending therefrom, of outriggers projecting from the fuselage at opposite sides thereof, and in front and rear of said wings, and front and rear sets of normally collapsed parachutes attached to said outriggers, and means for holding and releasing said parachutes and permitting them to spread, 80 and means for adjusting the angles of said parachutes in relation to the fuselage. 85

4. In a flying machine, the combination with the fuselage and wings extending therefrom, of outriggers projecting from the fuselage at opposite sides thereof, and in front and rear of said wings, and front and rear sets of normally collapsed parachutes attached to said outriggers, and means for holding and releasing said parachutes and permitting them to spread, 90 and means for simultaneously adjusting the angles of all of said parachutes in relation to the fuselage. 95

5. In a flying machine, the combination with the fuselage, and wings extending therefrom, of outriggers projecting from the fuselage at opposite sides thereof and in front and rear of said wings, and front and rear sets of normally collapsed parachutes attached to said outriggers, a transverse shaft to which each set of parachutes is fastened, pulleys on said shafts, and a cable passing over said pulleys for simultaneously turning said shafts. 110

6. In a flying machine, the combination with the fuselage, and wings extending therefrom, of outriggers projecting from the fuselage at opposite sides thereof and in front and rear of said wings, and front and rear sets of normally collapsed parachutes attached to said outriggers, a transverse shaft to which each set of parachutes is fastened, pulleys on said shafts, and a cable passing over said pulleys for simultaneously turning said shafts, and a motor for operating said cable. 120

7. In a flying machine, the combination

with the fuselage and wings extending therefrom, of outriggers projecting from the fuselage at opposite sides thereof, and in front and rear of said wings, and front 5 and rear sets of normally collapsed parachutes attached to said outriggers, a transverse shaft to which each set of parachutes

is fastened, pulleys on said shafts and a cable passing over said pulleys for simultaneously turning said shafts, and a switch controlled motor for operating said cable.

In testimony whereof I affix my signature.

CHESTER FRANK STANLEY.
